UNITED STATES PATENT OFFICE.

CARL BÖHME, OF SAN FRANCISCO, CALIFORNIA.

OIL-BURNER TIP.

1,051,069.

Specification of Letters Patent. Patented Jan. 21, 1913.

Application filed October 21, 1911. Serial No. 655,890.

To all whom it may concern:

Be it known that I, CARL BÖHME, a subject of the Emperor of Germany, residing in the city and country of San Francisco and 5 State of California, have invented new and useful Improvements in Oil-Burner Tips, of which the following is a specification.

This invention relates to oil burners and particularly to an improved tip for oil 10 burners.

The object of the present invention is to provide a simple, efficient tip for oil burners embodying details of construction and design rendering a single tip capable of producing flames of various size; and to provide a tip for oil burners, the flame of combustion of the gases being generated close to the orifice of the tip.

The invention consists of the parts, and 20 the construction and combination of parts as hereinafter more fully described and claimed, having reference to the accompanying drawings, in which—

Figure 1 is a perspective view of a burner 25 tip. Fig. 2 is a side elevation of the burner tip. Fig. 3 is a sectional view transversely through the burner tip. Fig. 4 is a detail view of the tip having an orifice of different design from Fig. 2.

It is the desideratum to provide a burner tip attachable to various forms of burner structures one of which is indicated in Fig. 2 at 2; such tip being capable of generating a small or a large flame with equal efficiency.

Many burners and tips as at present devised and used, result when in operation, in the generation of a blaze which is in a position considerably distant, varying in different conditions, from the immediate mouth of 40 the tip of the burner, and it is to provide a burner tip which will generate a flame in closer proximity to the tip orifice that I have provided a tip as indicated at 3, which has an internal thread 4 for the reception of a 45 supply pipe or burner body, the forward end of the tip being substantially hemispherical, as at 5. The interior of the tip, 3, is provided with a frusto-conical chamber, 6, the forward and smaller end of which intersects the base of a slit, 8, formed in the outer end of the burner and, in the form of burner shown in Fig. 3, there is a cylindrical extension, 9, of the forward end of the chamber, the diameter of this extension being in 50 excess of the width of the slotted forward portion of the burner whereby a transverse

wall, 7 is formed in front of but adjacent the base of the slit where it intersects the forward end of the conical chamber. It will thus be seen that the extended portion, 9, of 60 the chamber permits the combustible gases to advance well toward the outer end of the tip and results in the spread of the flame, as indicated in Fig. 3, during combustion.

I have found by actually constructing and 65 using the present burner under varying conditions, such for instance as under boilers of considerable horsepower, and also employing the same burner in a small household stove, that various forms and sizes of flames 70 can be generated by the combustible issuing from the tip.

When an extremely narrow or tongue-like flame is desired for certain conditions of 75 operation, as in Fig. 4, I omit the cylindrical portion 9 from the chamber 6', and cause the orifice slit or discharge mouth 8' to intersect with the plane of the wall 7', as indicated in Fig. 4.

One of the important objects of the present invention is to so design and construct the burner tip that the flame of combustion of the issuing mixture will take position relatively close to the end 5 of the tip and this I accomplish by forming upon or attaching to the burner tip a wind shield 10, of suitable proportion, and design, and which is here shown as being substantially rectangular, with one edge curved upwardly as at 11, and just below such edge forming a 80 perforation through which may project the burner tip. When the burner with this shield is erected in position in a furnace or stove, as in Fig. 2, the induced drafts coming through the orifice of the stove or furnace, may flow around the shield 10, but this acts to prevent the draft from drawing directly against the flame of combustion, thereby permitting this flame to creep toward or generate closer to the actual discharge orifice of the tip. This will be better understood by stating that if the wind shield 10 is not employed, then the induced air draft rushes along the surface of the tip 3 and will occasionally extinguish the flame of combustion, particularly if the burner is 85 being utilized with fluids under low pressure.

Having thus described my invention what 110 I claim and desire to secure by Letters Patent is:—

An improved burner tip having an in-

ternal chamber of frusto-conical form, said tip having a forward end provided with a slit which extends inwardly and has its inner end or base intersecting with and terminating at the forward and smaller end of the chamber, said chamber having a cylindrical portion about equal to the diameter of the smaller end of the chamber and forming an extension thereof, the diameter of said cylindrical extension being less than the width of the slit, whereby a transverse wall

is formed in advance of the base of the slit, said wall projecting across the path of the fuel delivered through the chamber.

In testimony whereof I have hereunto set 15 my hand in the presence of two subscribing witnesses.

CARL BÖHME.
